UNITED STATES PATENT OFFICE.

JOHN BRAYTON HARLOW, OF NEW YORK, N. Y., ASSIGNOR, BY MESNE ASSIGNMENTS, TO WESTERN ELECTRIC COMPANY, INCORPORATED, A CORPORATION OF NEW YORK.

RAILWAY SIGNALING SYSTEM.

1,373,503.

Specification of Letters Patent.

Patented Apr. 5, 1921.

Application filed April 9, 1915. Serial No. 20,221.

To all whom it may concern:

Be it known that I, JOHN BRAYTON HARLOW, a citizen of the United States, residing at New York, in the county of New York and State of New York, have invented certain new and useful Improvements in Railway Signaling Systems, of which the following is a full, clear, concise, and exact description.

10 This invention relates to railway signaling systems.

The object of this invention is to provide such a system by means of which a dispatcher or attendant at a central station may 15 determine when a train or car enters any particular section of track.

In accordance with this invention there is provided a signaling circuit extending from a central station along a railroad track divided into sections. With at least some of the sections of track, are associated signal sending devices set and conditioned for operation from the central station, the passing of a train or car into the sections causing the 25 signaling sending devices to send signals to the central station.

The drawing is a diagram of the apparatus and connections of a railway signaling system embodying this invention.

30 In the drawing, A designates a central or receiving station, B and C designate sections of a railroad track along which extend line wires 5 and 6 connected to the receiving or central station A.

35 Located at the central station is an impulse transmitting device 7 and a contact making device 8 in a local circuit including a source of energy 10 and the windings 11 of an impulse relay. The impulse relay includes normally open contacts 12 and 13 and a normally closed contact 14. The closure of the contacts 12 and 13 connects a source of current 15 with the line wires 5 and 6. The contact 14, in the operation of the impulse relay, opens and closes a bridge of the line including a non-inductive resistance 16, said bridge being open when the contacts 12 and 13 are closed, and closed when the contacts 12 and 13 are open, the purpose being

40 to provide a low resistance discharge path for retardation coils 17, 17 and 18, 18, in series with the line wires and a condenser 19 in bridge of the line wires. The retardation coils and the condenser are for the purpose

of graduating the current-impulses from the 55 impulse relay in order that they will not cause the disagreeable thump in telephonic apparatus which may be connected with the line wires during the transmission of the impulses.

50 Located at track section B is a step-by-step selective circuit closing device comprising a quick-acting magnet 25, and a slow-acting magnet 26 for operating the stepping and holding pawls 27 and 28 which control the 60 movement of a ratchet wheel 29. Carried by the ratchet wheel 29 is a contact arm 30, adapted in the movement of said ratchet wheel, to engage a contact spring 31. The selector is preferably arranged to be held 65 in its circuit closing position only when current is traversing the windings of its magnets. The selector may be connected in a local circuit controlled by a relay 35 in bridge of the line wires. Impulse transmitting key 7 at station A is for operating the selector at track section B.

65 A relay 39 and electromagnet 41 are under control of the selector and are actuated when contacts 30 and 31 are in engagement. The 70 electromagnet 41, upon energization, attracts an armature 42 which through a connecting arm 43 closes contacts 44, 45, 46, 47 and 48. Closure of contacts 44 and 45 establishes a locking circuit for electromagnet 41 through 75 winding 40 thereof. The armature 42 carries a pawl 49 which engages a ratchet wheel 50 mounted on one end of a shaft 51, upon the other end of which is mounted a contact controlling wheel 52 having a notched periphery. Engaging the notched periphery of wheel 52 is a spring contact member 53, and as shaft 51 is rotated under control of the pawl 49 and the ratchet wheel 50, a contact 54, controlled by the wheel 52 and the 80 member 53 is alternately closed and opened. A track relay 60 is bridged across the two rails of the track section B and is normally energized by current from a battery 61 located at one end of the section when there is 85 no train or car in the section. Armature 62 of track relay 60 is therefore normally in attracted position. A motor 65 is under the control of electromagnet 41 and the circuit thereof is closed when contact 48 is made. The motor 65 is adapted to drive a shaft 66 which carries code contact wheels 67 and 68. Contacts controlled by these wheels open and 90

100

105

close a circuit, causing signals to be sent to the receiving station through contacts closed by the operation of electromagnet 41. The position of an armature 63 of relay 64 determines which of the two code contact wheels 67 and 68 will send out a signal.

The motor 65 when started operates continuously to cause the proper code wheel to send out the proper signal until stopped by the attendant at station A. This is accomplished by actuating contact making device 3, causing relay 35 to complete a circuit for the other winding 85 of electromagnet 41, and since the direction of the flow of current through the two windings is opposed, the resulting magnetic action on the armature 42 is *nil*, whereupon the armature 42 releases.

There is associated with track section C, apparatus exactly like that shown for track section B, the position of the contact arm 30 of the selector being different from that at section B, so that each selector will respond to a different combination of current impulses. Likewise, the selectors provided with other track sections should have the contact arms 30 positioned differently from these at track sections B and C. The transmitting key 7 located at station A is for the purpose of calling station B, while key 7¹ is used for calling station C. It is to be understood that there should be one key for each track section equipped, or there may be one master transmitting key, such as is shown in Patent 1,155,340 to G. Brown, which may be set to control the sending out of a plurality of different combinations of impulses.

Referring now to the operation of the system it will be assumed that the operator at station A wishes to be advised whenever a train or car enters track section B. Accordingly, he will first operate the call transmitter 7. The operation of the call transmitter will operate the impulse relay and send current impulses from the source 15 over the line wires 5 and 6. These current impulses over the line wires will energize the relay 35, causing it to open and close its contact 70 included in a circuit which may be traced from the live pole of battery 71, through contact 70 of relay 35, stepping and holding magnets 25 and 26, to ground. The current impulses thus sent through the selector magnets cause the step-by-step advancement of the ratchet wheel 29 to close the contacts 30 and 31, whereupon an energizing circuit is closed for the relay 39 and the electromagnet 41. This circuit may be traced from the live pole of battery 72, winding 40 of electromagnet 41, winding of relay 39 and contacts 31 and 30 of the selector, to ground. Electromagnet 41, upon being energized, attracts its armature 42, thereby completing a locking circuit for itself from battery 72, through

winding 40 of electromagnet 41, resistance 73 and contacts 45 and 44, to ground. The attraction of armature 42 also caused the closure of contact 54, whereupon relay 64 is operated over a circuit from battery 78 through the winding of relay 64, normally closed contact 73 and armature 62 of track relay 60 and contact 54 to ground. When armature 42 was attracted, the motor 65 started to rotate due to the closure of the following circuit; from battery 78 through the winding of motor 65, through field winding 79 thereof and contact 48, to ground. Rotation of the motor 65 causes code contact wheel 67 to send a distinctive signal to the receiving station A, due to the alternate closing and opening of contact 30 in the circuit which may be traced from the lower brush of motor 65, contact 75 of relay 64, contact 30 of code wheel 67, contact 46, condenser 82, line wire 5, receiver 83 at station A, line wire 6, condenser 84, contact 47, and the upper brush and armature of motor 65. The source of energy for this circuit is the counter-electromotive force in the armature of motor 65.

The opening and closing of this circuit causes a tone to be produced in the receiver 83, indicating to the operator at station A that the signal sending device associated with the track section B has been set. The operator, having satisfied himself by the operation of his signal that the apparatus at track section B has been set, operates key 8 which causes the impulse relay to close the circuit from battery 15, through the relay 35. Relay 35 in operating, causes electromagnet 41 to release which opens the signal circuit and the operating circuit of motor 65 which stops. The release of electromagnet 41 is brought about by the closure of the circuit which may be traced from the live pole of battery 71 through contact 70 of relay 35, contact 77 of relay 39, winding 85 of electromagnet 41 and contact 44, to ground.

The direction of the flow of current through the two windings of electromagnet 41 is opposite, therefore rendering this electromagnet differential and the windings being the same, the magnetic effect of one neutralizes that of the other, and armature 42 releases. The release of the armature opens the locking circuit for winding 40, electromagnet 41. It is to be noted that upon the release of electromagnet 41, contact 54 remains closed.

Subsequent to the release of the electromagnet 41, a train or car 90 enters track section 89, whereupon through the wheels and axle of the train or car, track relay 60 is short-circuited and releases. In releasing, track relay 60 causes the operation of electromagnet 41 over a circuit from the live pole of battery 72, through winding 40 of electromagnet 41, contact 91 and armature 62 of

track relay 60, and contact 54 to ground. The release of track relay 60, also causes the release of relay 64. The operation of electromagnet 41 closes its locking circuit and the 5 operating circuit of the motor 65 hereinbefore traced, whereupon the motor 65 rotates. The rotation of motor 65 causes code contact wheel 68 to send a distinctive signal to the receiving station A indicating that a 10 train has entered track section B. This signal is produced by the alternate closing and opening at contact 81 of the circuit which may be traced from the lower brush of motor 65, through armature 63 and contact 59 of 15 relay 64, contact 81 of code contact wheel 68, contact 46, condenser 82, line wire 5, receiver 83 at station A, line wire 6, condenser 84, contact 47, and the upper brush and armature operator 65. The opening and closing 20 of this circuit causes a tone to be produced in receiver 83.

The passing of a train or car out of track section B again energizes track magnet 60, but the signal sending device at track section 25 B will continue to send out a signal until the electromagnet 41 is released by the operation of the key 8 at the station A, after which all apparatus returns to normal condition as indicated in the drawing.

30 While a plurality of batteries have been shown at the track section it is to be understood that this is for convenience only and that in practice one battery is substituted therefor. However, track battery 61 is separated and distinct from the battery which is associated with the other apparatus.

What is claimed is:

1. In a railway signaling system, a receiving station, a railroad track divided into sections, a line circuit extending from said receiving station along said railroad track, a signal sending device at each of a plurality of said sections, an operating circuit therefor, an electromagnet controlling said operating circuit and the connection of said signal sending device with said line circuit, a selectively operated device controlled over said line circuit from said receiving station, a track controlled device, and an energizing 50 circuit for said electromagnet jointly controlled by said selectively operated device and said track controlled device.

2. In a railway signaling system, a receiving station, a section of railroad track, a line circuit extending from said receiving station to said section, a signal sending device at said section, an operating circuit therefor, an electromagnet controlling said operating circuit and the connection of said signal 60 sending device with said line circuit, an energizing circuit for said electromagnet open at two points, means at said section controlled over said line circuit from said receiving station for controlling the closing of said energizing circuit at one point, and a

track controlled device for completing said energizing circuit at the other point when a train enters the section.

3. In a railway signaling system, a receiving station, a railroad track divided into sections, a line circuit extending from said receiving station along said railroad track, a signal sending device at each of a plurality of said sections, an operating circuit therefor, an electromagnet controlling said operating circuit and the connection of said signal sending device with said line circuit, an energizing circuit for said electromagnet open at two points, a selectively operated device controlled from said receiving station for controlling the closing of said energizing circuit at one point, and a track 70 relay controlled by a train entering the section for closing said energizing circuit at the other point.

4. In a railway signaling system, a receiving station, a railroad track divided into sections, a line circuit extending from said receiving station along said railroad track, a signal sending device at each of a plurality of said sections, an operating circuit therefor, an electromagnet controlling said operating circuit and the connection of said signal sending device with said line circuit, an energizing circuit for said electromagnet 75 open at two points, a selectively operated device controlled from said receiving station for controlling the closing of said energizing circuit at one point, and a track relay controlled by a train entering the section for closing said energizing circuit at the other point.

5. In a railway signaling system, a receiving station, a railroad track divided into sections, line wires extending from said receiving station along said railroad track, a signal sending device at each of a plurality of said sections, an operating circuit therefor, an electromagnet controlling said operating circuit and the connection of said signal sending device with said line wires, an energizing circuit for said electromagnet having two branches, the first open at one point and the second open at two points, a selectively operated device controlled from said receiving station for completing said first branch, the operation of said electromagnet closing said second branch at one point, and a track relay controlled by a train entering the section for closing said second branch at the other point.

6. In a railway signaling system, a receiving station, a railroad track divided into sections, a line circuit extending from said receiving station along said railroad track, a signal sending device at each of a plurality of said sections, an operating circuit therefor, an electromagnet controlling said oper- 125

- ating circuit, and when operated, connecting the signal sending device to the line circuit, a selectively operated device controlled over said line circuit from said receiving station, a track relay; and an energizing circuit for said electromagnet jointly controlled by said selectively operated device when selected and said track relay when a train enters the section.
- 10 7. In a railway signaling system, a receiving station, a railroad track divided into sections, a line circuit extending from the receiving station along the track, a signal sending device at each of a plurality of said sections, an electromagnet when oper-

ated connecting the signal sending device to the line circuit and causing the operation thereof, a selectively operated device, a track relay, and an energizing circuit for said electromagnet jointly controlled by said selectively operated device when selected and said track relay, when a train enters the section.

In witness whereof, I hereunto subscribe my name this 8th day of April, A. D. 1915. 25

JOHN BRAYTON HARLOW.
